JOHN A. FLEMINGS, OF SHARON, MASSACHUSETTS, ASSIGNOR TO B. F. STURTEVANT COMPANY, OF HYDE PARK, MASSACHUSETTS, A CORPORATION OF MASSACHUSETTS.

FUEL-FEEDING MECHANISM FOR UNDERFEED STOKERS.

Application filed April 26, 1923. Serial No. 634,801.

The invention relates to means for feeding fuel to underfeed stokers.

Stokers of this character are usually provided with one or more retorts, into the front end of which the fuel is forced by a feeding plunger, and from the open top of which the fuel spreads laterally onto the fuel supporting surfaces or grates at the side or sides of the retort. The fuel fed in by the plunger may be moved along the bottom of the retort, to secure the proper distribution to the fuel bed, by a series of pushers secured to a reciprocating pusher bar which is usually located within and close to the bottom of the retort.

One object of the present invention is to provide a construction and arrangement of pushers which will avoid the buckling or springing upward of the bar and the attached pushers under the resistance offered by the fuel to the advance of the pushers, or by reason of the packing of the fuel between the bottom of the retort and the bar or pushers. This is accomplished by providing the pusher blocks with ribs which project laterally into longitudinal guiding grooves formed in the side walls of the retort and preferably at the base of each wall. With this construction the pushers slide along the bottom of the retort and are maintained in fixed relation thereto by the ribs and grooves so that vertical movement of the pushers within the retort is prevented.

A further object of the invention is to provide for the adjustment of the pushers on the pusher rod to vary their distributing effect on the fuel without disturbing the fuel bed or requiring the removal of the fuel from the retort. This is accomplished by mounting the pusher bar in a slot passing through the bottom of the retort so that the bar is accessible from the under side of the retort and by also providing means for connecting the pushers with the bar which may be manipulated from the under side of the retort to connect and disconnect the pushers. With this construction the pushers may be adjusted in setting up the stoker to secure the proper distribution of the fuel or the location of any pusher may be readily varied at any time during the use of the

stoker to vary the distribution without removing or disturbing the fuel bed. The adjustments may, therefore, be made under operating conditions and the desired distribution be secured and maintained without inconvenience and loss of time.

Either feature outlined above may be utilized in combination with or independently of the other, and a construction embodying both features is shown in the drawings. Fig. 1 is a vertical sectional view through the center of the fuel retort of an underfeed stoker, Fig. 2 is a transverse sectional view on a larger scale taken on the line 2—2, Fig. 1, and Fig. 3 is a sectional detail on line 3—3, Fig. 2.

In the construction shown fuel is fed into the forward end of the retort 2 by the feeding plunger 4 which is reciprocated by the crank 6 and connecting rod 8 and forces the fuel from the hopper 10 through the feed throat 12 in the usual manner.

The fuel is moved along in the retort by a series of pushers 14 which cooperates with the plunger in forcing the fuel up between the tuyere blocks 16 so that it spreads over the upper surfaces of the blocks and of the usual grate surfaces arranged at the sides of the retort. The pushers are in the form of blocks arranged to slide along the stationary bottom 18 of the retort and retained and guided by ribs 20 which project from the sides of the blocks into longitudinal guiding grooves 22 formed at the bases of the side walls 24 of the retort. By this construction the pushers are positively and uniformly guided and their vertical relation to the bottom of the retort and to the fuel therein is maintained with a resulting uniform action on the fuel.

The pusher blocks are reciprocated by a rectangular pusher bar 26 which fits within and fills a slot 28 in the bottom of the retort. The slot extends through the bottom of the retort and the bar is supported in the slot by a series of short cover plates 30 which underlie the bar and are bolted to flanges 32 on the under side of the retort bottom. By removal of one or more of the cover plates access may be had to the bar from below the retort at any desired point or points for

- 2
- the purpose of adjusting one or more of the pushers on the bar. To enable this adjustment to be conveniently made while the fuel remains in the retort each pusher is connected with the bar by two pins 34 which may be inserted in any pair of two series of holes 36 formed in the bar. The lower ends of the holes are countersunk to receive the heads of the pins which are retained in the holes by the cover plates. The upper ends of the pins project above the upper surface of the bar and engage the opposite ends of the corresponding pusher blocks. When a pusher block is to be adjusted the cover plates which normally underlie the two series of holes 36 corresponding to the pusher to be adjusted are removed to give access to the pins 34. One of the pins is then shifted into the hole corresponding to the desired position of the pusher, the bar 26 is then moved to bring this pin into engagement with the end of the pusher, which movement will uncover the other pin hole 36 of the pair corresponding to this position of the pusher so that the other pin may be inserted in the bar. The cover plates are then replaced so that the pins are retained in their readjusted positions. The relative positions of the pushers on the bar may thus be quickly and conveniently shifted to vary the distribution of the fuel in the fuel bed without disturbing the fuel or requiring any material interruption in the operation of the feeding mechanism. The adjustments may be made under operating conditions and consequently the most efficient distribution may be secured and maintained.
- The bar 26 is reciprocated from the feeding plunger by a lug 38 secured to the under side of the plunger and arranged to engage or play between lugs 40 which are adjustably secured to the bar to vary the lost motion between the plunger and bar and thus the movement given to the bar by the reciprocation of the plunger.
- While it is preferred to employ the specific construction and arrangement of parts shown and described it will be understood that this construction and arrangement is not essential to the broader features of the invention and may be varied or modified as found desirable or best suited to the construction and mode of operation of the stoker in which it is to be embodied.
- 55 What is claimed is:
1. An underfeed stoker having, in combination, a horizontal fuel retort provided with longitudinal guiding grooves, pushers spaced along the bottom of the retort and arranged to move back and forth relatively thereto, and adapted to feed fuel upwardly through superposed horizontal tuyere blocks, ribs on the pushers projecting into the grooves, and a push bar connected to the pushers for reciprocating the latter.
  2. An underfeed stoker having, in combination, a horizontal fuel retort, each side wall of which is provided at its base with a longitudinal groove, pushers spaced along the bottom of the retort and arranged to move back and forth relatively thereto and adapted to feed fuel upwardly through superposed horizontal tuyere blocks, ribs on the pushers projecting laterally into the grooves, and a push bar connected with the pushers for reciprocating the latter.
  3. An underfeed stoker having, in combination, a fuel retort provided with a longitudinal slot extending through its bottom, a push bar in the slot, pushers in the retort, and devices accessible from the under side of the retort for adjustably connecting the pushers with said push bar.
  4. An underfeed stoker having, in combination, a fuel retort provided with a longitudinal slot extending through its bottom, a rectangular push bar filling the slot, pushers in the retort overlying the bar, devices accessible from the under side of the retort for adjustably connecting the pushers with the bar, and a series of removable cover plates underlying the bar.
  5. An underfeed stoker having, in combination, a fuel retort having a longitudinal slot extending through its bottom and a longitudinal groove along the base of each side wall, a push bar in the slot, pushers in the retort provided with ribs extending laterally into the grooves, and devices accessible from the under side of the retort for adjustably connecting the pushers with the bar.
  6. An underfeed stoker having, in combination, a fuel retort having a longitudinal slot extending through its bottom and a longitudinal groove along the base of each side wall, a push bar in the slot, pushers in the retort provided with ribs extending laterally into the grooves, two series of holes in the bar corresponding to each pusher, two pins for each pusher, each pin passing through one of a pair of holes in the two series and engaging opposite ends of the corresponding pusher, and a series of removable cover plates underlying the bar.
  7. An underfeed stoker having, in combination, a fuel retort having a longitudinal slot extending through its bottom, a push bar in the slot, pushers in the retort, two series of holes in the bar corresponding to each pusher, and two pins for each pusher, each pin passing through one of a pair of holes in the two series and engaging opposite ends of the corresponding pusher.
  8. An underfeed stoker having, in combination, a fuel retort provided with oppositely disposed longitudinal guiding grooves, a plurality of spaced separated pushers aligned in the bottom of the retort and having ribs projecting laterally into the grooves, and a push bar extending beneath the push-
